CLAIM

The ornamental design for a convex block, as shown and described.

DESCRIPTION

FIG. 1 is a front perspective view of a convex block showing my new design;

FIG. 2 is a top plan view thereof;

FIG. 3 is a front elevational view thereof;

FIG. 4 is a bottom plan view thereof;

FIG. 5 is an end elevational view, the opposite end being a mirror image thereof;

FIG. 6 is a rear elevational view thereof;

FIG. 7 is a front perspective view of a second embodiment of a convex block showing my new design;

FIG. 8 is a top plan view of FIG. 7;

FIG. 9 is a front elevational view of FIG. 7;

FIG. 10 is a bottom plan view of FIG. 7;

FIG. 11 is a side elevational view of FIG. 7, the opposite side being a mirror image thereof;
FIG. 12 is a rear elevational of FIG. 7;
FIG. 13 is a front perspective view of a third embodiment of a convex block showing my new design;
FIG. 14 is a top plan view of FIG. 13;
FIG. 15 is a front elevational view of FIG. 13;
FIG. 16 is a bottom plan view of FIG. 13;
FIG. 17 is an end elevational view of FIG. 13, the opposite end being a mirror image thereof;
FIG. 18 is a rear elevational view of FIG. 13;
FIG. 19 is a front prospective view of a fourth embodiment of the convex block showing my new design;

FIG. 20 is a top plan view of FIG. 19;
FIG. 21 is a front elevational view of FIG. 19;
FIG. 22 is a bottom plan view of FIG. 19;
FIG. 23 is a side elevational view of FIG. 19, the opposite side being a mirror image thereof;
FIG. 24 is a rear elevational view of FIG. 19;
FIG. 25 is a front perspective view of a fifth embodiment of a convex block showing my new design;
FIG. 26 is a top plan view of FIG. 25;
FIG. 27 is a front elevational view of FIG. 25;
FIG. 28 is a bottom plan view of FIG. 25;
FIG. 29 is a side elevational view of FIG. 25, the opposite side being a mirror image thereof; and
FIG. 30 is a rear elevational view of FIG. 25.
